(57) **CLAIM**

The ornamental design for a wrapping sheet for packaging an electronic device, as shown and described.

DESCRIPTION

This application is related to U.S. application Ser. No. 29/891,238, filed on even date herewith, entitled "Wrapping Sheet for Packaging an Electronic Device" and U.S. application Ser. No. 29/891,239, filed on even date herewith, entitled "Wrapping Sheet for Packaging an Electronic Device", both of which are hereby incorporated by reference as if set forth in their entirety herein.

FIG. 1 is a perspective view of a wrapping sheet for packaging an electronic device showing my new design; FIG. 2 is a top view thereof, the bottom view being a mirror image of the top view;

FIG. 3 is a front side view thereof, the rear side view being a mirror image of the front side view; FIG. 4 is a left side view thereof, the right side view being a mirror image of the left side view;

FIG. 5 is a top view of the first embodiment shown in a first open configuration with an unclaimed device to be wrapped and positioned thereupon; FIG. 6 is a perspective view thereof; FIG. 7 is the perspective view thereof now shown in a second partially wrapped configuration; and,

FIG. 8 is the perspective view thereof now shown in a third fully wrapped configuration. The shade lines indicate the character and contour of the surfaces represented, not to be confused with surface ornamentation.

The dashed lines in FIGS. 5-8 depict an electronic device that is wrapped by the wrapping sheet for packaging an electronic device, wherein the electronic device forms no part of the claimed design. The dashed lines in FIG. 8 depict environmental structure that forms no part of the claimed design. The shading in FIGS. 5-8 represent a translucent material for the wrapping sheet for packaging an electronic device and is not to be confused with surface ornamentation.

(Continued)

Portions of the dashed lines in FIGS. 7-8 appearing behind the wrapping sheet for packaging an electronic device are farther apart to represent an obscured appearance through the translucent layer(s) of the wrapping sheet for packaging an electronic device.
